US00D669942S

(12) **United States Design Patent**
Mimlitch, III et al.

(10) **Patent No.:** **US D669,942 S**
(45) **Date of Patent:** **** Oct. 30, 2012**

(54) **ROBOT ATTACHMENT**

(75) Inventors: **Robert H. Mimlitch, III**, Rowlett, TX (US); **David A. Norman**, Greenville, TX (US); **Douglas Galletti**, Allen, TX (US); **Joel Carter**, Argyle, TX (US); **Gregory Needel**, Rockwall, TX (US); **Jeffrey Russell Waegelin**, Rockwall, TX (US)

(73) Assignee: **Innovation First, Inc.**, Greenville, TX (US)

(**) Term: **14 Years**

(21) Appl. No.: **29/400,209**

(22) Filed: **Aug. 24, 2011**

(51) **LOC (9) Cl.** **21-01**

(52) **U.S. Cl.** **D21/578; D21/650**

(58) **Field of Classification Search** D6/596; D11/158; D30/160; D21/576, 578-585; D21/650, 658-659; 446/72, 97-98, 268-269, 446/356, 369, 377

(57) **CLAIM**

The ornamental design for a robot attachment, as shown and described.

DESCRIPTION

FIG. 1 is a top perspective view showing a first embodiment of the robot attachment;

FIG. 2 is a bottom perspective view of FIG. 1;

FIG. 3 is a front side view of FIG. 1;

FIG. 4 is a back side view of FIG. 1;

FIG. 5 is a top side view of FIG. 1;

FIG. 6 is a bottom side view of FIG. 1;

FIG. 7 is a left side view of FIG. 1;

FIG. 8 is a right side view of FIG. 1;

FIG. 9 is a top perspective view showing a second embodiment of the robot attachment with a toy robot in dotted lines;

FIG. 10 is a bottom perspective view of FIG. 9;

FIG. 11 is a front side view of FIG. 9;

FIG. 12 is a back side view of FIG. 9;

FIG. 13 is a top side view of FIG. 9;

FIG. 14 is a bottom side view of FIG. 9;

FIG. 15 is a left side view of FIG. 9; and,

FIG. 16 is a right side view of FIG. 9.

The broken lines are for the purpose of illustrating portions of the environmental structure and forms no part of the claimed embodiment and design.
